UNITED STATES PATENT OFFICE

FRANZ HEINRICH BENNO STELZER, OF DRESDEN, GERMANY, ASSIGNOR TO THE FIRM
"UNIVERSELLE" CIGARETTENMASCHINEN-FABRIK J. C. MULLER & CO., OF DRESDEN, GERMANY

TOBACCO SPREADER

Application filed August 17, 1929, Serial No. 386,557, and in Germany August 27, 1928.

Several forms of tobacco spreaders have been proposed in which the tobacco fibres are drawn by a suction device arranged on the upper side of a moving sieve surface on to the lower surface of the sieve so the lower side of the moving sieve surface is covered with a tobacco fleece which at the other end of the suction device is delivered to a feed band located beneath the sieve surface. The delivery of the fleece presents difficulties. Since the external air entering the suction device also passes around the edge of the suction hopper and enters the hopper the end of the fleece moving out of the range of the suction hopper is rolled back on itself instead of being released in the desired manner from the sieve surface and settles on the tobacco covering the sieve surface forming a layer of gradually increasing thickness which finally falls off in lumps. In order to avoid this disadvantage it has been suggested to shape the suction hopper in such manner as to form at the end of the suction area a gap tapering gradually towards the sieve surface and thus throttling the supply of air to the end of the suction area.

In accordance with the present invention quite as reliable and satisfactory removal of the tobacco fleece from the moving sieve surface is obtained by forming the feed band receiving the fleece also as a moving sieve and arranging under the flight feeding the fleece forwards a corresponding suction device. It is possible also in this way by imparting greater speed to the feed band to stretch the fleece and to dress its fibres by drawing them apart. The arrangement in accordance with the invention will conceivably be most effective when used with the form of suction hopper previously described on the fleece forming moving sieve. It may, however, be otherwise applied where this particular form of the suction hopper is absent.

The invention is illustrated in the accompanying drawing in which Fig. 1 shows the present arrangement of tobacco spreader in conjunction with a moving sieve in the form of an endless band and with a suction hopper such as described above, in vertical lon-

gitudinal section. Fig. 2 shows a modification.

Referring to Fig. 1 of the drawing 1 is a tobacco hopper the bottom of which is formed by the feed band 2 leading the tobacco fibers to the moving sieve. The feed band 2 pushes the tobacco fibres towards the plate 3 which acts as a stripper and is assisted in this action by the compressed air nozzles 4. Beyond the latter is disposed a brushing roller 5 serving to render the fleece uniform. The endless sieve band 6 is guided over the three rollers 7. In the triangle thus formed is disposed the suction hopper 8 the wall of which defining the rear end of the suction area is shaped in the manner shown in the drawing so as to form a gradually tapering gap 8a. At the other side of the suction area is disposed a brushing roller 9 for cleaning the sieve band 6.

The feed band 10 receiving the fleece is also formed as a sieve and travels over the three rollers 11 so as itself to form a triangle in which is arranged the suction hopper 12. One wall of the hopper is also shaped in such manner as to form a gap 12a which gradually tapers towards the end of the suction area. The manner in which the transfer of the fleece from the moving sieve 6 to the feed band 10 in the overlapping portion of the two suction hoppers takes place depends on the relative degree of effective suction in the two suction hoppers. Preferably means are provided to control the suction action of the hopper 12 in relation to that of the hopper 8. In any case by virtue of the arrangement forming the subject of the present invention the fleece is freed with certainty and satisfaction from the sieve band 6 and it can be stretched and the fibres dressed by correspondingly arranging the speed of movement of the feed band 10. The release of the fibres from the feed band 10 is ensured as the fleece with the band 10 passes over the left hand roller 11.

Fig. 2 shows the arrangement in accordance with the invention in conjunction with a sieve drum 6' with a built-in suction hopper 8 which does not have the particular form of the suction hopper shown in Fig. 100

1. Here again between the flights of the sieve like feed band 10 passing over the rollers 11 is disposed a suction hopper 12 adapted to the space available with a wall extending towards the feed band and forming a gap 12a for the purpose of gradually reducing the suction action.

10 In the foregoing description suction action and negative pressure have been discussed but in certain circumstances an effective drop of air pressure having the same effect can also be produced by using compressed air which naturally requires suitably shaped nozzles.

15 I claim:—

1. A tobacco spreader including suction means, perforated feed means moving over the suction means and adapted to take up the tobacco fibres at one point, a second perforated feed means at another point, a second suction means for said second feed means, and said first suction means having a gradually tapering area partly overlapped by said second feed means whereby the tobacco fleece is transferred from the first feed means to the second feed means.

2. Means for spreading cut tobacco comprising, a moving perforated member for carrying a tobacco fleece, means for creating suction through a portion of said member, means near the delivery point of the latter for reducing said suction action gradually whereby said fleece may be removed, means for receiving said removed fleece and transporting the latter to the desired point, said last named means including a moving perforated member arranged adjacent the delivery point of said first named perforated member, means for creating suction through a portion of said second named perforated member and means for reducing the suction action therethrough adjacent the delivery point of said second named member.

3. Means for spreading cut tobacco comprising a moving perforated member for carrying a tobacco fleece, suction means adapted to act through a portion of said member, a second perforated member adjacent the delivery point of said first named member receiving said fleece, suction means adapted to act through a portion of said second named member and means for reducing the suction action therethrough adjacent the delivery point of said second named member.

4. Means for spreading cut tobacco comprising a moving perforated member for carrying a tobacco fleece, suction means adapted to act through a portion of said member to carry said fleece and means for removing the latter from said member and stretching the same, said means including a second movable perforated member adjacent the delivery point of said first named member, suction means adapted to act through a portion of said last named member and means for re-

ducing the suction action therethrough adjacent the delivery end thereof.

5. In a device as per claim 4, in which said second named suction means includes a hopper the open end of which is adapted to lie beneath said second named perforated member, said hopper being shaped towards the delivery end to gradually reduce the space between the wall of said hopper and said member whereby the suction action will be gradually reduced adjacent said delivery end of said member.

6. In a tobacco spreader, a conveyor, means for brushing the tobacco at the end of said conveyor to render the tobacco fleece uniform, a feed subjected to suction adapted to pick up the tobacco from said conveyor and a second feed subjected to suction of which the suction area partly overlaps the suction area of and which is adapted to receive the tobacco fleece from said first named feed, the transfer of the tobacco fleece from one of said feed to the other being dependent on the relative degree of effective suction.

20 In testimony whereof I affix my signature.
